RECEIPT MECHANISM

Herman F. Sadgebury, Dayton, Ohio, assignor,
by mesne assignments, to Central United Na-
tional Bank, Cleveland, Ohio, as trustee

Application April 6, 1932, Serial No. 603,594

5 Claims. (Cl. 101—66)

In the patent of Albert S. Wheelbarger and Grover C. Coil, No. 1,858,813, issued May 17, 1932, a ticket issuing machine was shown which issues a ticket on every operation of the machine. 5 In some stores the merchants do not wish receipts on every operation of the machine but only occasionally care for such receipts and in case they do not need the receipt they do not wish it to be issued, for if the unneeded receipts 10 fall on the floor they are simply litter. The object of this invention is to provide a machine of the type shown in the said application but provided with an optional receipt feature.

In the drawings: 15 Fig. 1 is a side elevational view of a machine such as shown in the said application but having my invention incorporated thereon;

Fig. 2 is a cross sectional view thereof; 20 Fig. 3 is a perspective view; and Fig. 4 is a detail perspective view of the mechanism mounted on one of the printing shafts.

The gear 1 is rotated by any convenient means not shown, which gear meshes with and drives a gear 2 secured to a Geneva gear 3 provided with 25 a circumferential disk 4 extending for approximately 270 degrees. This disk 4 holds the Geneva pinion 5 stationary until the teeth of the Geneva gear 3 pick up and actuate the Geneva pinion 5, as is well known in the art, 30 the object being that in spite of the fact that the Geneva gear 3 and disk 4 are much larger than the Geneva pinion 5, the Geneva pinion 5, the Geneva gear 3 and the disk 4 will be rotated once for each operation of the machine. The 35 Geneva pinion 5 meshes with and drives a pinion 6 loosely mounted on the shaft 7. The shaft 7 is provided with an electrotype 8 which presses a ticket strip 9 into engagement with a feed roller 10 mounted on the shaft 11.

40 A hand lever 12 is pivoted on a stud 13 and is provided with a notch 14 and a notch 15. One or the other of these notches is engaged by a retaining pawl 16 mounted on a stud 17 which pawl is pulled into engagement with one or the 45 other of the notches by means of a spring 18. A lever 12 is provided with an arm 19 which terminates in an overturned lug 20 adapted, under certain conditions, to engage a notch 21 in a disk 22 which is integral with a pinion 23. The 50 disk 22 and pinion 23 are fast on the said shaft 7. The condition under which the overturned lug will engage the notch 21 is when the lever 12 is so positioned that the pawl 16 will engage the notch 14, which might be called the "off" notch, thereby holding the disk 22 and shaft 7 against

any tendency to rotate. The arm 19 is provided with a slot 24 which receives a pin 25 carried by an arm 26 pivoted on a shaft 27. The arm 26 is provided with a stud 28 which carries a broad pinion 29 sufficiently wide to engage both 60 of the pinions 6 and 23. The slot 24 might be called a cam slot for if the hand lever 12 is shifted from the position shown in Fig. 1 to a position such that its notch 15 will be in engagement with the pawl 16, the said notch 24 will 65 cam the pin 25 outwardly so as to bring the broad pinion 29 into mesh with the pinions 6 and 23. If the machine is now operated it is obvious that when the loosely mounted pinion 6 is rotated by means of the Geneva pinion 5 it will rotate the 70 pinion 23 through the pinion 29 and thereby rotate the shaft 7 and the electroplate 8 and feed the ticket out of the machine.

It is, therefore, thought that it is apparent that when the hand lever 12 is in the position 75 shown in Fig. 1 the ticket feeding mechanism will not be operated but if it is in a position such that the pawl 16 engages the notch 15 the pinion 29 will connect the pinions 6 and 23 so that when the machine is operated the ticket will be issued. 80 The only thing that the operator need do to change from a ticket issuing machine to one which does not issue a ticket is simply to shift the lever 12.

In the said patent, however, the ticket is printed 85 each time the machine is operated and it is, of course, obvious that the ticket should not be printed unless it is going to be issued. I have, therefore, provided means to render inoperative the ticket printing mechanism in case the ticket 90 issuing mechanism is disabled as above described. In other words, if a ticket is going to be issued it must be printed but if it is not going to be issued, the ticket ought not to be printed. In order to 95 secure these results I have connected the hand lever 12 to a link 30 by means of a pin 31. The lower end of this link 30 is provided with a pin 32 which is mounted on a crank arm 33 secured to a shaft 34 which is provided with a second crank arm 35 connected to a link 36 by means of a pin 37. The lower end of the link 36 is provided with a pin 38 mounted on a lever 39 pivoted on a shaft 40. This lever 39 is provided with a pin 41 which extends through a slot 42 in the frame 43. When the lever 12 is so positioned that the pawl 16 engages the "off" notch 14 the links 30 and 36 are in their lowered position and the pin 41 would be at the bottom of the slot 42. If now the printing carrier 44 is oscillated 105 by means of the pitman 45 connected to the 110

Geneva gear 3 by means of a wrist pin 46 the lever 47 mounted on the shaft 48 and normally movable with the printing carrier 44 would pass above the pin 41 but if the hand lever 12 is shifted so that the notch 15 is engaged by the pawl 16, which it will be remembered would cause the issuing mechanism to become operative, the pin 41 would be raised to the upper end of the slot 42 so that as the printing carrier 44 was oscillated the pin 41 would engage the lower end of the lever 47 and hold it against oscillation thereby bringing its cam surface 49 on the upper portion thereof into engagement with the platen 50 mounted on a shaft 51 which is mounted in a slot 52 in the side arms of the printing carrier thereby elevating this platen into engagement with the printing wheels 53.

By the above described means the operator can either print and issue a ticket or by simply shifting a lever he can disable both the ticket printing and ticket issuing means.

I realize that many changes may be made in the specific form of this invention shown and described by way of illustration in this application and I, therefore, reserve the right to make such changes in the specific form of the invention as shown herein as I may find to be desirable. I, therefore, claim the invention broadly except as I may limit myself by the appended claims.

Having now described my invention, I claim:

1. In a register, a platen, a feeding means comprising a rotatable printing plate and platen, a lever, and means controlled by said lever to free said first mentioned platen and to lock said feeding means against operation when said lever is in a predetermined position.

2. In a register, a feeding means, a pinion secured thereto, a driven pinion rotatably mounted on said feeding means, a lever, and a pinion carried thereby and adapted to engage both of the pinions mounted on said feeding means when said lever is moved to a certain position. 80

3. In a register, a feeding means, a pinion secured thereto, a driven pinion rotatably mounted on said feeding means, a lever, a pinion carried thereby and adapted to engage both of the pinions mounted on said feeding means when said lever is moved to a certain position, and means to lock said feeding means against operation when said lever is in another of its positions. 85

4. In a register, a feeding means, a pinion and a disk provided with a notch secured to said feeding means, a pinion loosely mounted on said feeding means, a lever having two significant positions, a pinion and a lug carried by said lever, said pinion on said lever engaging both of the pinions on the feeding means when the lever is in one of its positions and said lug engaging said notch to lock said feeding means against operation when the lever is in the other of its positions. 90

5. In a register, an oscillating printing carrier provided with slots, a platen supporting means for said platen extending into said slots, printing characters, a lever, and means whereby when said lever is in a certain position said platen will be elevated into engagement with said printing characters and when said lever is in another position said platen will not be elevated. 105
